UNITED STATES PATENT OFFICE.

PETER G. GIROUD, OF NEW YORK, N. Y.

DESIGN FOR A CLOCK-CASE.

No. 39,942.

Specification for Design.

Patented April 27, 1909.

Application filed February 24, 1909. Serial No. 479,850. Term of patent 7 years.

To all whom it may concern:

Be it known that I, PETER G. GIROUD, a citizen of the United States, and resident of the borough of Manhattan, in the city and State of New York, have invented a new, original, and ornamental Design for a Clock-Case, of which the following is a specification, reference being had to the accompanying drawing, forming part thereof.

Figure 1 is a face view of a clock case,

showing my new design, and Fig. 2 is a side view of the same.

I claim:—

The ornamental design for a clock case, as shown.

PETER G. GIROUD.
